(57) **CLAIM**

I claim the ornamental design for a curved hinge hanger with an elongated vertical tube, as shown and described.

DESCRIPTION

FIG. 1 is an isometric top view of a curved hinge hanger with an elongated vertical tube, showing my new design; FIG. 2 is an isometric bottom view thereof;

FIG. 3 is a front elevation view thereof;

FIG. 4 is a left elevation view (at 90° from the front view) thereof;

FIG. 5 is a back elevation view thereof;

FIG. 6 is a bottom view thereof; and,

FIG. 7 is a top view thereof.

The broken lines shown represent unclaimed subject matter and form no part of the claimed design.

1 Claim, 3 Drawing Sheets

FIG. 3

FIG. 4
